UNITED STATES PATENT OFFICE.

JOHN SUTINEN, OF TWO HARBORS, MINNESOTA.

RAIL BRACE.

Application filed November 30, 1928. Serial No. 322,877.

This invention relates to railroad rail bracing devices and has special reference to such devices particularly adapted for use upon metal railroad ties such for example as illustrated in my Patent 1,697,935, granted January 8, 1929, though adaptable to other forms of metal as well as wooden ties, if desired.

The principal object of the invention is to provide a bracing member susceptible of adjustment at any time for tightening or loosening the same.

Other objects and advantages of the invention will appear in the following description thereof.

Referring now to the accompanying drawing, forming part of this application, and wherein like reference characters indicate like parts:

20 Figure 1 is a cross section of a metal tie having a bearing surface for the railroad rail, and to which the brace is shown as applied in Figures 2 and 3.

Figure 2 is a fragmental portion of one end of the tie with the rail shown in cross section and the brace in elevation.

Figure 3 is a plan view of Figure 2, a portion of which is shown in section;

30 Figure 4 is a plan view of the wishbone brace;

Figure 5 is an elevation of the adjusting bolt for application to the brace;

35 Figure 6 is a perspective view of the fragmental end portion of the modified form of tie shown in my copending application; and

Figure 7 is a perspective view of a modified form of brace.

40 1 represents a somewhat novel form of tie to which the invention is applied, the rail being mounted directly over the angularly shaped housing 2, (one of which is provided adjacent each end of the tie), about the wooden block 3 for proper holding of the rail spikes 4.

45 Through the rail engaging flange 5 of the tie and spaced intermediate of the end of the tie and the rail is formed a through hole indicated at 6 to provide convenient means for fastening the brace. This latter is illustrated at 7 and is of wishbone shape, constructed of suitable yieldable round material, the apex of the brace being flattened

or provided with a transverse portion as indicated at 8, and the legs normally diverging outwardly therefrom. 55

In Figures 2 and 3 I have shown an upstanding staple 9 as a means for securing the apex of the brace to the upper surface of the tie, and it is apparent that this staple may be replaced by an eyebolt, an upset clip 60 from the flange of the tie, or if the apex of the brace is bent downwardly as shown at 15 in Figure 7, it may simply extend within a hole 6 and function in all respects in like manner to that shown in Figures 2 and 3 65 of the drawings.

The legs of the brace are adjustably united as by the transverse bolt 10, it being hook shaped as at 11 at one end and being screw threaded upon the other end and provided 70 with a suitable nut 12 and hook washer 13. The hooked end of this bolt is designed to overlap one leg of the brace, while the hook washer engages the other leg, and by means of the nut 12 adjustment of the brace accomplished by the bolt. Non-slipping connection of the hooked end of the adjusting bolt to one leg of the brace is provided by a hump or lump 14 being formed upon the outer wall of one leg, either by sharply arching same, or the pinching outwardly of a 75 bulge therein as more clearly shown in Figure 7, and common in the art of mechanics. 80

In Figure 6 is shown a modified form of 85 tie, in the upstanding web 17 of which an inclined notch 18 is formed, into which the flattened apex of the brace may be dropped for satisfactory anchorage. The bent apex 15 as shown in Figure 7 of the drawings 90 may be sharpened so as to be driven into the upper surface of a wooden tie and there held by a common staple, if desired.

Having thus described my invention, what I claim and desire to secure by Letters 95 Patent, is:

1. A rail brace comprising a member bent upon itself forming spaced diverging termini, means for anchoring the apex of the member, and means for adjusting the free 100 ends of the member to and from each other for the purpose described.

2. The combination with a tie of the class described, of a rail brace comprising a sub-

stantially V-shaped member, means for anchoring the apex of said member to the tie, and means for adjusting the free ends of the member to and from each other.

5 3. A brace of the class described comprising a member bent upon itself forming spaced diverging termini, means for piv-

otally anchoring the apex of the member, and means for adjustably moving the free ends of said member to and from each other ¹⁰ for the purpose described.

In testimony whereof I affix my signature.

JOHN SUTINEN.
